UNITED STATES PATENT OFFICE

HAROLD L. DE LISLE, OF CHICAGO, ILLINOIS

BINDER FOR DOWN-HANGING SHEETS

Application filed December 30, 1927. Serial No. 243,630.

The present improvements relate to binders of the kind adapted to hold down-hanging blue prints and the like. It is old to provide a pair of strips or clamping members adapted to be positioned face to face and having bolts transversely through them for holding the sheets. According to such prior practice the sheets were required to be perforated to accommodate the bolts, the bolts passing through edge portions of the sheets. Such perforation not only requires considerable time but in some instances mutilation of the sheets is objectionable. Furthermore, in applying such perforated sheets to the binder it has been necessary to remove the clamping nuts from the bolts, then remove one of the clamping members or strips, then place the sheet in position on the bolts or remove it therefrom as the particular instance requires, then replace the binding strip, and then re-apply the nuts. Such older practice is therefore quite inconvenient, causes much loss of time, and is otherwise objectionable.

It has also been suggested heretofore to dispense with the transverse bolts and hold the sheets between interiorly recessed strips through the clamping action of springs pressing the strips toward each other, as witness the U. S. patent to Newbaker, No. 636,166 of October 31, 1899, and that to Memmler, No. 1,165,108 of December 21, 1915.

While various objections to the spring-clip type of sheet-holder might be pointed out, it will be sufficient here to indicate that the objects of these improvements include the provision of a simple and cheap binder of the character described having few parts and parts not likely to get out of order, and in which a single sheet or a considerable number of sheets may be conveniently inserted and removed, and in a brief space of time, and be firmly and securely held against retraction throughout a long period of use, and to provide a construction by which the individual holders may occupy but relatively small space whereby a relatively large number of such holders may be placed side by side in a cabinet of given depth and the capacity of the cabinet thereby increased. The present invention provides improved advantages

also in accessibility to particular ones of the holders when normally arranged in the cabinet of file holder over such devices are shown in the patents mentioned. Other objects and advantages will appear hereinafter. 55

In the accompanying drawings, which form a part of this specification, Figures 1, 2, 3 and 4 are top, front, bottom and rear views respectively of the preferred form of device complete; Fig. 5 is an enlarged fragmentary broken face view of the device of Fig. 1 held by lateral rack bars of the kind shown in side view in Fig. 8; Fig. 6 is an enlarged sectional view as on the line 6—6 of Fig. 5; Fig. 7 is a fragmentary detail showing the application of a staple for holding the bolt; Fig. 8 shows a modified construction for the device when made of metal; and Fig. 9 is a fragmentary view of the inner face of the rear clamping member. 60 65 70

According to my preferred construction the binding members 10 and 11 are of wood. When made from thirty-four to thirty-six inches in length they will accommodate blue prints, tracings, etc. of the larger sizes ordinarily found, but the length of these members may be increased or decreased according to particular needs. In my practice the wood strips 10 and 11 are approximately one and one quarter inches high and about five-sixteenths of an inch in thickness. They are preferably made of well seasoned hardwood. It is advantageous to have the strips fairly thin whereby a considerable number of them may be positioned side by side in a cabinet 75 80 85 of given depth.

From Fig. 6 it will well be noted that the strips or binding members 10 and 11 are provided with recesses as 12 and 13 respectively on their normally inner surfaces, these recesses extending from near the top edges of the binding members to near their bottom edges respectively and being defined by upper rib-like extensions 14 and 15 respectively and lower rib-like extensions 16 and 17 respectively. When these opposed rib-like extensions abut each other the recesses 12 and 13 coalesce to form a hollow interior extending from end to end of the strips. 90 95

A plurality of bolts 20 (ordinarily four 100

will be quite ample) are carried by the rear binding member 11, the heads of the bolts being flush with the rear surface of the strip in order to save space. A staple 21 positioned in the kerf of each bolt-head holds the bolt against retraction and also against turning.

The bolts 20 are positioned substantially midway between the top and bottom of the 10 binding members and extend through the binding member 10. A nut member 23 having a relatively long sleeve 23^a is threaded upon the free end of the bolt. This sleeve 23^a may well extend entirely through the 15 strip 10. The hole 24 in the strip through which the sleeve 23^a extends is considerably larger in diameter than the sleeve to permit a tilted position of the sleeve therein. A washer 25 having a substantially spherical 20 bearing surface lies between the outer flange of the nut 23 and a concave seat formed in the strip 10. The washer 25 also has a hole sufficiently larger in diameter than that of the sleeve 23^a to permit of its adjusting itself 25 to provide a firm seat between the nut member and the strip 10 when the bolt is at a diagonal with respect to the strip 10.

The construction and arrangement are such that the upper rib-like extensions 14 and 15 30 constitute a fulcrum while the lower rib-like extensions 16 and 17 constitute jaws for gripping a single sheet or a considerable number of sheets, the power being applied between the fulcrum and the work and there- 35 by constituting the device a lever of the third class.

The relatively long sleeve 23^a not only provides for such a large amount of threaded area as adds life to the threaded members, 40 but, importantly, it provides that the bolt 20 may be much shorter than would be the case if an ordinary nut were applied resting against the outer face of the strip 10, and thus the construction shown economizes space 45 in the direction of the thickness of the device and enables the holders complete to be positioned in the cabinet relatively close to each other.

The nut members 23 have their outer edges 50 milled whereby they may easily be gripped by the fingers. In applying sheets or removing them the binder complete is first removed from the rack and laid upon a table. The nut members 23 are then retracted, and for 55 removing sheets a slight retraction is sufficient while for replacing sheets the retraction of the nuts must of course be sufficient to allow the jaws at 16 and 17 to spread the required distance. In inserting the sheets their edges are simply pushed between the jaws and within the hollow interior of the device. It 60 is sufficient if they simply enter the structure well within the gripping area of the jaws, but ordinarily they are pushed inward until 65 they come against the bolts 20 which serve

as stops providing the desired right-angular relation of the sheets to the binder. The hollow interior space between the bolt and the jaws provides ample room for the upper ends of the sheets so that the full gripping effect 70 is had at the jaws. When the nut members are tightened upon the bolts it is not necessary that a great deal of force be employed, and the holding effect of even a slight tightening of the nuts is surprisingly great. This 75 makes for notable ease in operation both in tightening and in releasing the nuts.

The rear strip or binding member 11 is preferably sufficiently longer than the front strip 10 to permit the device to be held in the rack 80 merely by the rear strip. This feature is not new in itself.

A card holder 26, Fig. 2, is adapted to show data concerning the prints or other subject matter within a particular file. When the 85 binders are held in such a rack as is shown in Fig. 8 they may be tilted back to disclose such data for ready reference.

According to Fig. 8 the binding members 30 and 31 are pressed from sheet material such as iron, the upper edge portions being extended at 31 to form a fulcruming seat. This figure also shows how such devices may be held in rack members 33 held by cabinet 95 walls 34 (Fig. 5).

I contemplate such modifications also as are included in the appended claims.

I claim:

1. A binder for down-hanging sheets comprising a pair of long and thin strip-like members face to face and formed trough-like interiorly in the longitudinal direction and having fulcruming surfaces at their upper edge portions and binding surfaces at their lower edge portions respectively, and a plurality of bolts carried by one of said members intermediate the top and bottom edge portions thereof and projecting transversely of said members, with a nut on each of said bolts bearing against the other one of said members for drawing the members toward each other for clamping sheets between said binding surfaces, at least one of said members extending at each end thereof beyond the sheet material normally held in the device 115 whereby the device as a whole may be supported at its opposite end portions.

2. The combination of claim 1 hereof in which said nuts respectively comprise a sleeve-like part projecting into the body of one of said members.

3. The binder of claim 1 hereof in which said nuts respectively comprise a sleeve-like part projecting into the body of one of said members, in combination with a washer on said sleeve-like part having a substantially spherical convex surface engaging a substantially spherical concave recess formed in the adjacent one of said members.

HAROLD L. DE LISLE.
